Specification for Design.

Patented May 17, 1921.

Application filed November 2, 1920. Serial No. 421,421. Term of patent 14 years.

To all whom it may concern:

Be it known that I, FRANK J. SHIVELY, a citizen of the United States, residing at Canton, in the county of Stark and State of Ohio, have invented a new, original, and ornamental Design for Knife-Handles, of which the following is a specification, reference being had to the accompanying drawing, forming part hereof.

I claim:
The ornamental design for a knife handle, as shown.

FRANK J. SHIVELY.
